US00D502210S

(12) **United States Design Patent** (10) Patent No.: **US D502,210 S**
Katori et al. (45) Date of Patent: **** Feb. 22, 2005**

(54) **COPYING MACHINE WITH FACSIMILE**

(75) Inventors: **Takehito Katori, Kanagawa (JP); Junichi Ogawa, Saitama (JP)**

(73) Assignee: **Matsushita Electric Industrial Co., Ltd., Osaka (JP)**

(**) Term: **14 Years**

(21) Appl. No.: **29/196,429**

(22) Filed: **Dec. 29, 2003**

(30) **Foreign Application Priority Data**

Sep. 11, 2003 (JP) 2003-026584

(51) **LOC (7) Cl.** **16-03**

(52) **U.S. Cl.** **D18/39; D14/463**
